DESIGN FOR A COMBINED TELEPHONE SUPPORT, ASH TRAY, AND AMPLIFYING LOUD SPEAKER

John Douglas Chirite, Detroit, Mich.

Application March 17, 1947, Serial No. 137,682

Term of patent 14 years.

(Cl. D26—14)

To all whom it may concern:

Be it known that I, John Douglas Chirite, a citizen of the United States, residing at Detroit, in the county of Wayne and State of Michigan, have invented a new, original, and ornamental Design for Combined Telephone Support, Ash Tray, and Amplifying Loud Speaker, of which the following is a specification, reference being had to the accompanying drawing, forming part thereof.

Fig. 1 is a side elevational view of the combined telephone support, ash tray and amplifying loud speaker, showing my new design;

Fig. 2 is a rear end view of the combined telephone support, ash tray and amplifying loud speaker;

Fig. 3 is a top plan view of the telephone support, ash tray and amplifying loud speaker;

Fig. 4 is a front elevational view of the tele-

phone support, ash tray and amplifying loud speaker; and

Fig. 5 is a sectional view taken on line 5—5 of Fig. 1.

I claim:

The ornamental design for a combined telephone support, ash tray and amplifying loud speaker, as shown.

JOHN DOUGLAS CHIRITE.
